UNITED STATES PATENT OFFICE.

WALTER ROSLUND, OF CLEVELAND, OHIO, ASSIGNOR TO THE AMERICAN COACH AND BODY COMPANY, OF CLEVELAND, OHIO, A CORPORATION OF OHIO.

VEHICLE WINDOW AND GUARD.

Application filed December 26, 1922. Serial No. 609,035.

To all whom it may concern:

Be it known that I, WALTER ROSLUND, a subject of the Government of Denmark, residing at Cleveland, in the county of Cuyahoga and State of Ohio, have invented certain new and useful Improvements in Vehicle Windows and Guards, of which the following is a specification.

This invention relates to windows, and especially to windows for vehicles of various kinds, such as motor busses, street cars and the like, and has for its object to provide an improved guard in connection with a window pane or sash, the arrangement being such that when the window is opened the guard will be raised in position to prevent the arms or heads of passengers from being extended outside of the window.

I am aware that guards have been provided with sliding windows, but as a rule they are separate structures placed for example outside of the window. By means of the present invention the pane and guard are secured together and they are lifted and dropped together to open or close the window, the guard sliding in the same grooves as the pane, and supporting the latter in its various positions.

In the accompanying drawings Fig. 1 is a side elevation of a motor bus provided with the improvement. Fig. 2 is an enlarged side elevation of the guard. Fig. 3 is a vertical section on the line 3—3 of Fig. 1. Fig. 4 is an upper edge view of the guard. Fig. 5 is a section on the line 5—5 of Fig. 1.

In the drawings, 11 indicates the side bars or stiles of a window casing in a vehicle in which the window is used, this casing being grooved as usual to receive the sliding sash which includes a pane of glass 6 which may be used without a frame, the edges of the glass sliding in a groove 8 in packing 9 set in a groove 10 in each stile.

The lower edge of the glass rests in a groove 5 extending along the upper edge of the top bar of the guard or grating 12, the lower edge of the pane being fixed in the groove by cement. The preferred method of making this joint is to cement a felt packing 7 in the groove and then to cement the lower edge of the pane in the packing, so that a water tight joint is produced. The grating is of substantially the same thick-

ness and width as the pane, so that both will slide in the same groove 8, the head 13 which is formed at the top of the grating, and which contains the groove 5, being cut off at the ends, as indicated at 13^a so that the ends of this head will abut against the strips or ribs which define the groove 10 in the stiles. This head may also be provided with ears 19 for the attachment of any suitable sash holding device for holding the sash at the desired elevation.

The window casing construction is of that type in which the pane may be raised into a casing above the window opening and the grating may be lowered into a casing below the window opening, the outer wall of said casing being indicated at 16 and provided at the top with a ledge 15 along which extends a packing strip 14 against which the outside of the head 13 closes when the sash is lowered, as shown at Fig. 3.

With a sash so constructed the pane and grating are fixed together and are raised or lowered together. When raised, the grating will rise from the well below to cover the window opening, the pane sliding into the casing above, and when the sash is lowered the grating will descend into the well until the head 13 rests on the packing strip 14 giving a close and water tight joint at the bottom of the window.

The device will be found very convenient and useful under all conditions where a guard is needed for the purpose indicated, and the structure is neat in appearance.

I claim:

1. In a window, a pane, and a guard secured to the lower edge of the pane, said pane and guard being slidable together up and down, the upper edge of the guard being provided with a groove in which the lower edge of the pane fits.

2. The combination with a window casing, of a sliding pane therein, and a guard secured to the lower edge of the pane slidably therewith, the guard being substantially the same width and thickness as the pane, the guard having a head at its upper edge with a groove in which the pane is held.

3. The combination with a window casing, of a sliding pane therein, and a guard secured to the lower edge of the pane slidably therewith, the guard being substantially

the same width and thickness as the pane,
the guard having a head at its upper edge
with a groove in which the pane is held, the
head being of less length than the width
of the guard and having an outstanding
shoulder which closes against the window
ledge when the guard is lowered.

In testimony whereof, I affix my signature
in presence of two witnesses.

WALTER ROSLUND.

Witnesses:
